UNITED STATES PATENT OFFICE.

GEORGE A. JOHNSON, OF CHICAGO, ILLINOIS, ASSIGNOR TO WILLIAM H. MINER, OF CHAZY, NEW YORK.

YOKE FOR RAILWAY DRAFT-RIGGING.

1,286,598.

Specification of Letters Patent.

Patented Dec. 3, 1918.

Application filed January 8, 1918. Serial No. 210,866.

To all whom it may concern:

Be it known that I, GEORGE A. JOHNSON, a citizen of the United States, residing at Chicago, in the county of Cook and State 5 of Illinois, have invented a certain new and useful Improvement in Yokes for Railway Draft-Rigging, of which the following is a full, clear, concise, and exact description, reference being had to the accompanying 10 drawings, forming a part of this specification.

This invention relates to improvements in yokes for railway draft riggings.

The object of the invention is to provide 15 a yoke for railway draft riggings which is so designed as to permit employment of the numerous small size draw bars now in service with yokes of larger and more modern size.

20 In the drawing forming a part of this specification, Figure 1 is a part longitudinal, vertical, sectional view, part side elevation of a draw bar and yoke showing my improvements in connection therewith. Fig. 2 is a transverse, vertical, sectional view taken 25 on the line 2—2 of Fig. 1. Fig. 3 is a horizontal, sectional view taken on the line 3—3 of Fig. 1. And Fig. 4 is a detail perspective of one of the filler blocks employed with 30 my improvements.

In said drawing, 10 denotes the shank of a draw bar having a butt 11 shouldered in the usual manner, as indicated at 12 and 13, the draw bar illustrated in the drawing being of an old type wherein the height of the draw bar butt is considerably less than in the more modern type of draw bar. The height of the draw bar butt illustrated may be considered as $6\frac{1}{2}$ inches and the spacing 35 between the arms of the yoke may be considered as $9\frac{1}{2}$ inches. The yoke, designated generally by the reference A, comprises upper and lower arms 14 and 15, rear connecting portion 16 and a hollow rectangular 40 head at the forward end. Said hollow head is formed by the forward ends of the yoke arms and by vertical side walls 17—17. On the interior, the hollow head is provided at the front end thereof with upper and 45 lower transversely extending gibs 18—18 spaced apart sufficiently to permit the insertion of the draw bar butt by longitudinal movement. Similarly, the interior of

the head is provided near the top and bottom thereof with vertically extending 55 shoulders 19—19 on the sides for the purpose hereinafter described, the space between said shoulders 19—19 being left great enough, however, to avoid interference with the butt of the draw bar when the latter is inserted. 60

To form the proper connection between the draw bar and the yoke under draft after the draw bar butt is inserted within the yoke, filler blocks B—B are employed. Each 65 of said filler blocks comprises a main portion 20 corresponding to the length of the butt and of sufficient thickness to take up the space between the butt and the adjacent horizontal wall of the yoke head. At its forward end, each block B is provided with 70 a transverse gib or shoulder 21 to engage the adjacent shoulder 12 or 13 of the draw bar butt. On its outer face, each block B is provided with another shoulder 22 to 75 coöperate with the adjacent gib or shoulder 18 of the yoke. The blocks B are also made of sufficient width as to provide vertical shoulders 24—24 at the sides to engage and coöperate with said shoulders 19 and in addition, each block B is provided with a forward extension or flange 25 adapted to substantially fill the space between the edge of the adjacent gib 18 and the shank of the coupler.

In assembling the parts, the butt of the 80 draw bar is first inserted within the hollow head and then the filler blocks are applied from the interior of the yoke. After the blocks are positioned on the draw bar butt, the blocks and butt are pulled forwardly 85 until the parts assume the position shown in the drawing.

With my arrangement, I obtain a strong construction and it will be noted that the transverse shoulders 24—24 of the liner 90 blocks are not only reinforced against pulling strains by the flanges 25 but are additionally supported at their ends by means of the side shoulders 19. In this way, I minimize any tendency of the transverse 95 gibs or shoulders of the blocks to bend under draft while at the same time the blocks are of simple form which can be easily and cheaply manufactured. With my arrangement, railroads are enabled to reemploy the 100 old couplers of small size with draft gears 105

of larger and more modern size and to effect a detachable draw bar and yoke connection at small expense.

I claim:

- 5 1. In a device of the character described, the combination with a yoke having a hollow head at its forward end and through which a shouldered draw bar butt is adapted to be inserted longitudinally, said hollow head 10 being provided with upper and lower transverse gibs and vertically extending shoulders on the sides thereof, of filler blocks adapted to be inserted between the upper and lower walls of the head and the upper and lower 15 surfaces of the draw bar butt, said filler blocks having transverse shoulders coöperable with said gibs and the shoulders of the butt, the forward portions of said blocks being extended laterally and adapted to engage behind said vertical side shoulders of the yoke head.

2. The combination with a draw bar having a shouldered butt, of a yoke having a hollow head at the forward end thereof within which the butt is adapted to be inserted longitudinally, said head being provided with transversely extending upper and lower gibs and vertically extending side shoulders adjacent said gibs, and filler blocks interposed between the butt and adjacent 25 walls of the yoke head, each of said filler blocks having transverse shoulders coöperable with the corresponding yoke gib and butt shoulder, said blocks at their edges engaging said vertical shoulders and having 30 also forwardly extended flanges in line with the shoulders of the butt.

In witness that I claim the foregoing I have hereunto subscribed my name this 29th day of Dec. 1917.

GEORGE A. JOHNSON.
